CLAIM

The ornamental design for a wristband sanitizer dispenser, as shown and described.

DESCRIPTION

FIG. 1 is a perspective view of a wristband sanitizer dispenser.

FIG. 2 is a perspective view thereof.

FIG. 3 is a perspective view thereof, with environment.

FIG. 4 is a top view thereof.

FIG. 5 is a bottom view thereof.

FIG. 6 is a right-side view thereof, with the left-side view being a mirror image.

FIG. 7 is a sectional view thereof, illustrating the profile of the interior cavity.

FIG. 8 is a front view thereof; and,

FIG. 9 is a rear view thereof.

The broken line showing of parts of the drawings is included for the purpose of illustrating use and environment, and forms no part of the claimed design.
